UNITED STATES PATENT OFFICE.

FRANK L. EIDMANN, OF NORTH BERGEN, NEW JERSEY, ASSIGNOR TO HENRY S. GERMOND, JR., OF BAYONNE, NEW JERSEY.

SAFETY DEVICE FOR ELEVATING TRUCKS.

Application filed January 2, 1924. Serial No. 683,918.

This invention relates in general to a safety device to prevent accidental release of the elevating platform of lifting machines, such as elevating trucks, which comprise a main frame or support, an elevating platform to receive a load and movable up and down on said main frame, a lever or handle pivoted on the main frame and adapted to separably connect with said elevating platform to raise and lower the latter as the handle is swung about its pivot, and latch or detent means for holding said platform in elevated position after the handle is disconnected therefrom.

One object of the invention is to provide a device of the character described embodying novel and improved features of construction whereby descent of the elevating platform cannot take place until the lifting handle has been disconnected from said platform, so as to prevent possibility of the handle being accidentally forcibly swung upwardly by descent of the platform and injuring the operator.

Another object is to provide such a device which prevents operation of the latch or detent means holding the platform in elevated position, while the lifting handle is operatively connected to the platform, said device being automatically actuated by disconnection of the lifting handle from the platform to release the latch or detent means to permit operation thereof to allow the platform to descend.

A further object is to provide a device of the character described in combination with an elevating truck having the elevating platform provided with a link pivotally connected thereto and adapted to be separably connected to a lifting handle pivoted on the main frame of the truck to raise and lower said platform, and a latch to hold the platform in elevating position, said device serving automatically to prevent actuation of said latch while the handle is connected to the platform with the latter in elevated position and being automatically actuated by said link when the latter is disconnected from said handle to release said latch.

Other objects are to provide novel and improved construction and combination of said link and a gravity operated safety pawl adapted to normally and automatically engage said latch when the platform is in elevated position and connected with said handle to prevent operation of the latch; and to

obtain other results and advantages as may be brought out by the following description.

Referring to the accompanying drawings, in which like numerals of reference indicate the same parts throughout the several views,

Figure 1 is a fragmentary side elevation of the forward end of an elevating truck having a safety device embodying my invention applied thereto, showing the elevating platform in its lowermost position;

Figure 2 is a view similar to Figure 1, showing the position of the parts with the elevating platform intermediate its lowermost and uppermost positions;

Figure 3 is a similar view showing the elevating platform in its uppermost elevated position and with the handle still operatively connected to the platform and the safety device in operation;

Figure 4 is a similar view showing the handle disconnected from the platform and the safety device in inoperative position;

Figures 5 and 6 are transverse vertical sectional views through the truck taken on the line 5-6 of Figure 4 and looking in opposite directions, and

Figure 7 is a view similar to Figure 1 showing a modification of the safety device adapted to be utilized for actuating the connecting link between the handle and the platform into operative position.

In the specific embodiment of the invention shown on the drawings, the reference character A designates the frame of the truck which may be of any suitable construction and is mounted at the rear end on wheels 1 journaled on a transverse shaft 2 (see Fig. 5). The forward end of the frame A is provided substantially centrally of its width with a king pin 3 revolvably journaled in the frame and carrying at its lower end a pair of steering wheels 4, this construction enabling the truck to be steered by rotation of the king pin 3.

An elevating and load sustaining platform B is mounted on the frame A in such a manner that the truck may be pushed beneath a load which is spaced from the floor by means of skids, the said platform being adapted to be elevated on the frame A to raise the load from the floor onto the truck. Any suitable means may be utilized for so mounting the platform on the same, but in the present instance a pair of parallel links 5 is shown as pivotally connected between

the frame A and the platform B at each end so that forward motion of the platform causes oscillation of the parallel links 5 which in turn raises the platform on the 5 main frame. All of the above-mentioned construction is old and well known, and no claim to novelty is based thereon.

For the purpose of drawing the truck from place to place and steering the same, 10 the king pin 3 may be provided at its upper end with a bracket 6 formed with two upwardly projecting spaced ears 7 between which is pivotally mounted at one end on a pin 8 a draft handle 9, said handle being 15 adapted to swing about its pivot 8 in vertical planes and to revolve the king pin 3 by swinging of the handle in horizontal planes so as to steer the truck. The said handle is also adapted to be operatively connected 20 with the platform B to draw the same forwardly so as to oscillate the links 5 and elevate the platform.

For this purpose, the draft handle may be provided with a rearwardly projecting hook 25 10 adapted to cooperate with a link 11 pivotally connected at one end as at 12 to the forward end of the platform B. The free end of said link is preferably bifurcated with its arms connected by a pin 13 which is 30 adapted to engage the hook 10 of the handle, as shown by dotted lines in Figure 1 and in Figure 2, the hook 10 engaging the pin 13 between the arms of the link so that a limited relative lateral movement of the 35 handle and the link is permitted. The link 11 may be connected to the forward end of the platform in any suitable manner, but in the present instance I have shown the link connected to the front side of a skid stop 14 40 which forms the forward end of the platform B and is adapted to engage a skid to limit the movement of the truck beneath the skid bearing a load which it is desired to elevate and transport by the truck.

When the platform B is in its normal 45 lowermost position, the link 11 is swung rearwardly into a substantially vertical position against the skid stop 14, as shown by solid lines in Figure 1, and in this position 50 the handle 9 is free for drawing and steering the truck. When it is desired to elevate the platform B, the handle 9 is swung upwardly into a substantially vertical position, as shown by dot and dash lines in Figure 1, 55 after which the link 11 is manually swung forwardly, for instance by the foot of the operator, so that the pin 13 lies on the hook 10 of the handle. The handle 9 is then swung downwardly in a vertical plane, as 60 indicated by Figure 2, whereby the platform B is pulled forwardly and elevated by oscillation of the links 5. Any suitable means 65 may be employed for holding the elevating platform in its uppermost position, but in the present instance I have shown the for-

ward end of the platform B provided with a rearwardly facing lug 15 adapted to be engaged by the head 16 of a latch lever 17 pivotally mounted intermediate its ends at 70 18 on the forward end of the main frame A. The latch lever 17 is normally influenced into the path of the lug 15 by means of a spring 19, and as the platform B rises, the lug 15 slips beneath the head 16 of the lever 17, which then engages the rear face of the 75 lug to hold the platform against rearward movement and descent. The platform is shown in its uppermost position in Figure 3 of the drawings, and may be steered under ordinary conditions without throwing the 80 link rearwardly, due to the lateral play between the hook 10 and pin 13. After the platform has been raised to this position and it is desired to lower the platform, it is advisable to disconnect the link 11 from the 85 handle 9, and this disconnection is readily accomplished by swinging the handle 9 upwardly into the position shown by dot and dash lines in Figure 3 and then pushing the link rearwardly into contact with the skid 90 stop 14. To release the platform the forward end of the latch lever 17 is provided with a treadle 20 which may be depressed by the operator so as to disengage the head 16 of the lever from the lug 15 whereupon the 95 platform descends by action of gravity. Any known means, such as a dash-pot construction, may be utilized to retard the descent of the platform.

It is an important feature of my invention 100 to provide means for preventing operation of the latch lever 17 and descent of the platform B until the link 11 has been completely disconnected from the handle 9, whereby the possibility of the handle being forcibly 105 swung upwardly by descent of the platform in such a manner as to injure the operator, is obviated. For this purpose, I may provide a gravity actuated pawl 21 pivotally connected at one end 22 to the forward end 110 of the platform B, for instance to the skid stop 14, above the lug 15, the lower end of said pawl being normally positioned by action of gravity to engage the top of the head 16 of the latch lever 17 when the platform 115 is in its uppermost position and the link 11 connected to the handle 9. The pawl 21 is shown in operative relation to the lever 17 in Figure 3, and it will be obvious that with the pawl in this position the lever 17 cannot 120 be oscillated by pressure on the treadle 20.

It is also a feature of my invention to provide automatic means for releasing the lever 17 when the link 11 is disconnected from the handle 9. One possible manner of accomplishing this result consists in providing the link 11 with a laterally projecting lug 23 adapted to engage a similar lug 24 on the adjacent side of the pawl 21, so that as the link 11 falls rearwardly to its inoperative 130

position, the lug 23 engages the lug 24 and swings the pawl 21 rearwardly out of engagement with the latch lever 17, as shown in Figure 4. With the pawl 21 in this position, the latch lever 17 may be freely operated so as to permit descent of the platform B, but it will be observed that there is no possibility of the handle 9 being swung upwardly, since the pawl 21 is caused to release the lever 17 only after the link 11 has been completely disconnected from the handle 9. It will be noted that the link 11 may be simultaneously disconnected from the handle 9 and thrown rearwardly into inoperative position by a quick rearward swinging of the handle, the pin 13 riding along the handle so that the link is swung about its pivot 12 as the handle is moved rearwardly, as shown by dot and dash lines in Figure 3.

Under some conditions the load on the platform B is so close to or so overhangs the skid stop 14 as to render it difficult or impossible for the operator to reach the link 11 with his foot to pull it forwardly into engagement with the hook 10. To overcome this difficulty, I may provide the upper end of the pawl 21 with an upwardly and forwardly projecting treadle 27 so arranged as to be always accessible to the operator, as shown in Figure 7. With such a construction the link 11 may be thrown forwardly by merely pressing the treadle 27 rearwardly, the pawl 21 being thus swung on its pivot so that the lug 24 in engagement with the lug 23 on the link pushes the link forwardly as desired. This construction is further advantageous in that it is easier to push rearwardly on the treadle 27 than to pull forwardly on the link 11.

In the particular construction described the handle 9 is preferably provided with a lug 25 to engage the base of the bracket 6 and limit rearward swinging of the handle, as shown in Figure 4. Also to ensure proper engagement of the pawl 21 with the latch lever 17, the rear side of the free end of the pawl is provided with a lug 26 to engage the head 16 of the latch lever and prevent forward swinging of the pawl to a point beyond dead center between its pivot and the head 16 of the latch lever. It will be understood that the invention is also susceptible of use with a lifting device in which the means for holding the platform against descent, in this case the latch lever 17, is mounted on the platform instead of on the frame as herein illustrated, and with other types of holding means than the lever 17 and lug 15.

While I have shown and described the safety device as embodying certain details of construction and used in connection with a certain type of elevating truck, it will be understood that this is mainly for the purpose of illustrating the principles of the invention and that many modifications and

changes can be made in the detail construction of the device and the device used in connection with many other types of lifting machines, without departing from the spirit or scope of the invention. Therefore, I do not wish to be understood as restricting myself except as required by the following claims when construed in the light of the prior art.

Having thus described the invention, what I claim is:

1. In a lifting device, the combination of a main frame, an elevating platform movably mounted thereon, a lifting handle on said main frame for raising and lowering the platform, means for separably operatively connecting said handle to said platform to raise and lower the latter, means for holding said platform against accidental descent from its uppermost position, and means for releasably locking said holding means in operative position while said connecting means is operatively engaged with said handle, said last-mentioned means being actuated by said connecting means upon disconnection thereof from said handle to release said holding means.

2. The combination with a lifting device including a main frame, an elevating platform movably mounted thereon, a lifting handle on said main frame for raising and lowering the platform, means for separably operatively connecting said handle to said platform to raise and lower the latter, and a latch lever pivoted on said frame for releasably holding said platform against descent from its uppermost position, of means for releasably holding said latch lever in operative position, said holding means being actuated by said connecting means when the latter is disconnected from said handle to permit release of said latch lever from said operative position.

3. The combination with a lifting device including a main frame, an elevating platform movably mounted thereon, a lifting handle on said main frame for raising and lowering the platform, and means for separably operatively connecting said handle to said platform to raise and lower the latter, of means operable while said handle is connected to said platform and the platform is in its elevated position for preventing descent of said platform, and means for producing actuation of last-mentioned means by said connecting means when said handle and said platform are disconnected by said connecting means to permit descent of said platform.

4. The combination with a lifting device including a main frame, an elevating platform movably mounted thereon, a lifting handle on said frame to connect with said platform to raise and lower the same and be disconnected therefrom after the platform

4
has been raised, and releasable means for holding said platform in its elevated position, of gravity actuated means mounted on said platform to automatically separably engage said holding means when the platform is in its elevated position to positively prevent release of said holding means and thereby prevent descent of said platform, and means operable by disconnection of said handle from said platform for automatically actuating said gravity actuated means out of operative relation with said holding means.

5. The combination with a lifting device including a main frame, an elevating platform movably mounted thereon, a lifting handle on said main frame for raising and lowering the platform, and a link pivotally connected to said platform to separably connect with said handle for raising and lowering the platform, of means operable while said link is connected with said handle and said platform is in its elevated position for positively preventing descent of said platform, said means being actuated by said link when the latter is disconnected from the handle to permit descent of said platform.

6. The combination with a lifting device including a main frame, an elevating platform movably mounted thereon, a lifting handle on said main frame for raising and lowering the platform, and a link pivotally connected to said platform to separably connect with said handle for raising and lowering the platform, and releasable means for holding said platform in elevated position, of means operable while said link is connected with said handle and the platform is in its elevated position for preventing release of said holding means, said last-mentioned means being actuated into inoperative relation to said holding means by said link when the latter is disconnected from said handle.

7. The combination with a lifting device including a main frame, an elevating platform movably mounted thereon, a lifting handle on said main frame for raising and lowering the platform, a link pivotally connected to said platform to separably connect with said handle for raising and lowering the platform, and releasable means for holding said platform in elevated position, of gravity actuated means to automatically separably engage said holding means when the platform is in its elevated position and said link is connected to said handle to prevent release of said holding means, said gravity actuated means being actuated by said link into inoperative relation to said holding means when said link is disconnected from said handle.

8. The combination with a lifting device including a main frame, an elevating platform movably mounted thereon, a lifting

handle on said frame to connect with said platform to raise and lower the same and be disconnected therefrom after the platform has been raised, and means mounted on said frame to releasably engage said platform when the latter is in its elevated position to hold the platform against descent, of means mounted on said platform for preventing release of said holding means while the platform is in its elevated position, and means operable by disconnection of said handle from said platform to actuate said last-mentioned means and release said holding means.

9. The combination with a lifting device including a main frame, an elevating platform movably mounted thereon, a lifting handle on said frame to connect with said platform to raise and lower the same and be disconnected therefrom after the platform has been raised, and a latch lever pivoted on said frame to releasably engage said platform when the latter is in its elevated position, of means mounted on said platform to automatically separably engage said latch lever when the platform is in its elevated position to prevent releasing operation of said lever, and means operable by disconnection of said handle and said platform for actuating said last-mentioned means into inoperative relation to said latch lever.

10. The combination with a lifting device including a main frame, an elevating platform movably mounted thereon, a lifting handle on said main frame for raising and lowering the platform, a link pivotally connected to said platform to separably connect with said handle for raising and lowering the platform, and means mounted on said frame to releasably engage said platform when the latter is in its elevated position to hold the platform against descent, of means mounted on said platform to automatically separably engage said holding means and prevent release thereof while the platform is in elevated position, said last-mentioned means being actuated into inoperative relation with said holding means by said link when the latter is disconnected from said handle.

11. The combination with a lifting device including a main frame, an elevating platform movably mounted thereon, a lifting handle on said main frame for raising and lowering the platform, a link pivotally connected to said platform to separably connect with said handle for raising and lowering the platform, said link being adapted to be swung rearwardly about its pivot toward said platform when disconnected from said handle, and means mounted on said frame to releasably engage said platform when the latter is in its elevated position to hold the platform against descent, of a gravity actuated pawl pivotally mounted to swing in a vertical plane on said platform to separably

engage said holding means when the platform is elevated to prevent releasing operation of said holding means, said pawl being arranged to be engaged by said link and 5 forced into inoperative relation to said holding means as the link is swung rearwardly upon disconnection from said handle.

12. The combination with a lifting device including a main frame, an elevating platform movably mounted thereon, a lifting handle on said frame to connect with said platform to raise and lower the same and be disconnected therefrom after the platform has been raised, and a latch member 10 movable in a vertical plane to releasably engage said platform when the latter is in elevated position to hold the platform against descent, of a gravity actuated member pivotally mounted on said platform to swing in a vertical plane so that its lower end separably engages the top of said latch member on a dead center between said latch member and the pivot of said gravity actuated member when the platform is in elevated 15 position to prevent releasing operation of said latch member, and means for disengaging said gravity actuated member from said latch member by disconnection of said handle from said platform.

13. The combination with a lifting device including a main frame, an elevating platform movably mounted thereon, a lifting handle on said main frame for raising and lowering the platform, a link pivotally 20 connected to said platform to separably connect with said handle for raising and lowering the platform, said link being normally disconnected from said handle and in a substantially vertical position, and releasable 25 means for holding said platform in elevated position, of a lever pivotally mounted intermediate its ends on said platform and actuated by gravity so that one end thereof separably engages said holding means when 30 the platform is in elevated position and said link is connected to said handle to prevent

release of said holding means, said lever being engaged by said link and forced into inoperative relation to said holding means when said link is disconnected from the 50 handle and swung upwardly, said lever also serving to throw said link downwardly into engagement with said handle when pressure is exerted on the other end of said lever.

14. The combination with a lifting device 55 including a main frame, an elevating platform movably mounted thereon, a lifting handle on said main frame for raising and lowering the platform, and a link pivotally connected to said platform to separably connect with said handle for raising and lowering the platform, and releasable means for holding said platform in elevated position, of means operable while said link is connected with said handle and the platform 60 is in its elevated position for preventing release of said holding means, said last-mentioned means being engaged and actuated by said link into inoperative relation to said holding means when the link is disconnected 65 from the handle and thrown into its vertical position, said last-mentioned means being also manually operable to throw said link from its vertical position into engagement with said handle. 75

15. A lifting device comprising a main frame, an elevating platform arranged to move longitudinally when it is moved vertically, a latch adapted to hold said elevating platform against longitudinal movement 80 when said platform is in its elevated position, a pivotally mounted dog carried by said elevating platform and cooperating with said latch to hold the same in operative position, means mounted on said main frame 85 to be separably connected to said platform for raising the latter and moving it longitudinally, and means automatically actuated by disconnection of the last-mentioned means from said platform for moving said dog to 90 release it from said latch.

FRANK L. EIDMANN.
